(57) **CLAIM**

The ornamental design for a balance bike, as shown and described.

DESCRIPTION

FIG. 1 is a top, rear and left side perspective view of a balance bike showing my new design;

FIG. 2 is a bottom, front and right side perspective view thereof;

FIG. 3 is a left side elevation view thereof;

FIG. 4 is a right side elevation view thereof;

FIG. 5 is a rear elevation view thereof;

FIG. 6 is a front elevation view thereof;

FIG. 7 is a top plan view thereof;

FIG. 8 is a bottom plan view thereof; and,

FIG. 9 is an enlarged detail view of area 9 in FIG. 1.

The broken lines in the drawings illustrate the portions of the balance bike, which form no part of the claimed design.

The dash-dot-dash broken lines indicate the boundaries of the enlarged views and are used for annotative purposes only. They do not limit or define the scope of the claimed design.
